UNITED STATES PATENT OFFICE.

MATHEW M. SEDWICK, OF CHICAGO, ILLINOIS, ASSIGNOR TO CONTINENTAL CAN COMPANY, INC., OF NEW YORK, N. Y., A CORPORATION OF NEW YORK.

SEAMING HEAD FOR CAN-CLOSING MACHINES.

Application filed June 27, 1927. Serial No. 201,842.

The invention relates to new and useful improvements in seaming heads for can closing machines, and more particularly to a seaming head provided with a chuck and a body portion rotatable relative thereto, which body portion carries the seaming rolls for rolling a can end and flange on a can body into a double seam.

An object of the invention is to provide a seaming head of the above type, wherein the chuck has associated therewith, means for yieldingly engaging the seaming rolls for imparting rotation to the seaming rolls.

A further object of the invention is to provide a device of the above type, wherein the surface speed imparted to the seaming rolls varies with the change in diameter of the double seam as the parts are rolled into the seam, thus preventing a sliding of the seaming rolls on the metal.

These and other objects will in part be obvious and will in part be hereinafter more fully disposed.

In the drawings—

Figure 1 is a sectional view through a seaming head embodying my improvement, the section being taken through the second operation rolls;

Fig. 2 is an enlarged detail showing a portion of the can, the chuck and the seaming roll at the beginning of the second operation, and

Fig. 3 is a similar view of the parts at the completion of the second operation.

The invention is directed to a seaming head having a rotating chuck and seaming rolls which have interengaging parts. Either the chuck is rotated to rotate a can which is to be closed, or the chuck is stationary, and the body portion of the head rotated to cause the seaming rolls to travel about the can. The seaming rolls are preferably carried by levers which are cam-actuated for bringing the rolls into contact with the can end and for rolling the can end, together with the flange on the can body, into a double seam. The seaming head has a pair of opposed first operation seaming levers carrying seaming rolls, and also a pair of second operation levers carrying seaming rolls.

The invention is particularly directed to means associated with the chuck and rotating therewith, if the chuck rotates, or held stationary therewith, if the chuck stands

still, which means engages the seaming rolls for imparting rotation thereto. This means is a yielding means, and is so arranged that the point of contact with the seaming rolls for imparting rotation thereto is always at the same distance from the axis of the head as the contact point between the seaming roll and metal and moves inwardly toward the

axis as the parts of the metal are rolled into the double seam, so that the speed imparted to the seaming rolls will vary with the change in diameter of the double seam and thus prevent slippage of the seaming rolls on the metal. The purpose of the invention is to provide means of the above type for driving the seaming rolls through the impingement of the seaming rolls on the rotating means, so that the rolls are not rotated merely by their contact with the metal.

This provision of means for rotating the seaming rolls insures that the roll is constantly in movement so as to roll up on to the metal during the turning of the part into a double seam. Where the rolls are rotated solely through the contact with the metal, there are times when the seaming roll comes to a stop and slides. This results in what is usually referred to as "dead heads" having imperfect seams. By the use of my yielding means for rotating the seaming rolls, all liability of slippage is avoided.

Referring more in detail to the drawings, the seaming head includes a body portion 1 on which is mounted a chuck 2. This chuck is rotatable in a bearing. A spindle 3 is attached to the chuck for rotating the same. Instead of rotating the chuck, the body portion of the head may rotate about the chuck, in which case, the spindle will be used to hold the chuck from rotation. It is essential that either the body portion of the head rotate, carrying the seaming rolls mounted thereon around the can, or that the chuck rotate, in which case, the head is held stationary, and the can is rotated within the seaming rolls. The seaming rolls, according to the present embodiment of the invention, are mounted on levers. These levers are arranged in pairs, and each lever carries a seaming roll. In Fig. 1, there are shown two levers 4, 4 which carry seaming rolls 5, 5. These are the second operation seaming rolls. The first operation seaming rolls and levers for supporting the same are similar in construction to those shown in Fig. 1, except as

to the shaping of the seaming groove in the seaming rolls. The structure of the seaming head shown in part in the drawings, and the method of operating the same, is similar to that described in the patent granted I. F. Warme, June 24, 1919, No. 1,307,888, and illustration and description of the first operation seaming rolls and the means for operating the head and the spindle is not thought necessary. Each of the second operation levers is pivoted at 8, and these levers are swung on their pivots by a cam 9 which is mounted on the seaming head so that it may move longitudinally of the chuck spindle. This cam engages members 10 when it is moved in an endwise direction and swings the levers outwardly at their upper ends, thus causing the seaming rolls to engage a can end and roll the end and flange on the can end into a seam. It is understood, of course, that the first operation rolls perform their function by a preliminary rolling of the parts into a double seam, after which they are retracted, and the second operation rolls shown in the drawings, are brought into action for completing the double seam.

The chuck is provided with a portion 11 which is adapted to seat within the recess of the can end, which end is to be attached to the can body. The chuck is provided with an annular groove 12, and with a projecting annular portion 13 at the upper side of this groove 12. Each seaming roll is provided with an annular groove 14 forming spaced projecting members 15 and 16. The seaming roll is also provided with a seaming groove 17. The annular groove 14 receives the projecting portion 13 of the chuck. This interengagement of the chuck and the seaming rolls is of the usual character. The seaming rolls are held on the seaming levers by suitable bolts 18. Associated with the chuck 2 is a steel plate 19. This steel plate is clamped between the chuck 2 and the shoulder 20 on the spindle 3. The plate is thus rigidly attached to the spindle, so as to rotate with the spindle, if it is a rotating spindle, and to stand stationary with the spindle, if it is a stationary spindle type of head.

The upper wall of the annular projection 16 is cut away slightly so as to provide a shoulder 21. This steel plate 19 is so positioned relative to the annular projection 13 of the chuck that the outer edge portion of the projection 16 on the seaming rolls will wedge between the yielding plate 19 and said projecting portion 13, and be gripped by the spring plate. This gripping contact of the spring plate on the seaming rolls will cause the seaming rolls to rotate when the head travels about the spindle, or if the head is stationary and the spindle and spring plate rotate. It is understood, of course, that during the formation of the double seam, the

seaming rolls move inwardly toward the axis of the head. The first seaming operation rolls engage a flange on a can end and gradually cause it to turn underneath the flange on the can body, and the parts rolled to the position shown in Fig. 2 of the drawings. This is the position of the metal parts at the completion of the first operation in the double seaming, and at the beginning of the second operation in the double seaming. During the completing of the second operation, the second operation seaming roll also moves inwardly to the position shown in Fig. 3, as the metal parts are more closely rolled into a double seam and the over-all diameter of the seam decreases.

During the inward movement of the first operation rolls, the point of contact with the flexible plate 19 will move inward toward the axis of the head. The first operation rolls then are moved out of contact with the spring plate 19 and the second operation rolls coming into action, will make contact with the spring plate, and the line of contact therewith will gradually move in toward the axis of the head as the metal parts decrease in diameter due to the completing of the double seam. As the external diameter of the double seam decreases, the point of contact between these seaming rolls and the spring plate 19 shifts inwardly so that the surface speed imparted to the seaming roll by the spring plate 19 will vary to accord with the change in outer diameter of the double seam. Thus it is that the seaming rolls are driven at proper speed, even though the diameter of the metal where contact occurs between the rolls and the metal varies, so as to avoid a possible slippage between the seaming rolls and the metal parts. In other words, the seaming rolls are constantly rotating and traveling up on the metal as it is forced inwardly to complete the double seam.

The slippage which occurs in ordinary seaming heads, occurs more frequently between the second operation rolls and the metal parts, and I have, therefore, illustrated the second operation rolls and the method of driving said second operation rolls through connection with this yielding plate 19 associated with the chuck. It is understood, of course, that the first operation rolls are likewise driven in a similar manner, so that slippage is avoided either in the first operation rolls or in the second operation rolls.

The contact of the projecting portion 16 of the seaming roll with the annular projection 13 of the chuck is brought about solely by the yielding nature of the plate 19, and I do not, in any way, depend upon the thrust on the seaming roll on the metal incident to the forming of the double seam.

Having thus described the invention, what

I claim as new and desire to secure by Letters Patent, is—

1. A seaming head for closing machines including a chuck for engaging a can end and holding the same on the can body, a body portion, said chuck and body portion having a relative rotation, seaming levers carried by said body portion, a seaming roll mounted to rotate freely on each seaming lever, and yielding means associated with said chuck and adapted to engage the seaming rolls at the outer edge portion thereof for causing said seaming rolls to rotate on their respective levers.
2. A seaming head for closing machines including a chuck for engaging a can end and holding the same on the can body, a body portion, said chuck and body portion having a relative rotation, seaming levers carried by said body portion, a seaming roll mounted to rotate freely on each seaming lever, said seaming rolls and said chuck having inter-engaging parts, and a yielding means associated with the chuck for engaging the seaming rolls at the outer edge portion thereof for causing the same to rotate on their respective levers.
3. A seaming head for closing machines including a chuck for engaging a can end and holding the same on the can body, a body portion, said chuck and body portion having a relative rotation, seaming levers carried by said body portion, a seaming roll mounted to rotate freely on each seaming lever, a spring plate associated with said chuck, each seaming roll having an annular projection adapted to engage between said spring plate and the chuck during the seaming operation whereby said spring plate engages the seaming rolls and causes the same to rotate.
4. A seaming head for closing machines including a chuck for engaging a can end and holding the same on the can body, a body portion, said chuck and body portion having a relative rotation, seaming levers carried by said body portion, a seaming roll mounted to rotate freely on each seaming lever, a spring
5. A seaming head for closing machines including a chuck, a spindle, a yielding metal plate disposed between the chuck and spindle and rigid with said spindle, a body portion, said spindle and body portion having a relative rotation, seaming levers carried by said body portion, a seaming roll mounted to rotate on each seaming lever, said seaming roll having an annular projection adapted to engage between said spring plate and said chuck so as to be gripped by said spring plate during the seaming operation for causing the seaming rolls to rotate.
6. A seaming head for closing machines including a chuck, a spindle, a yielding metal plate disposed between the chuck and spindle and rigid with said spindle, a body portion, said spindle and body portion having a relative rotation, seaming levers carried by said body portion, a seaming roll mounted to rotate on each seaming lever, said seaming roll having an annular projection adapted to engage between said spring plate and said chuck so as to be gripped by said spring plate during the seaming operation for causing the seaming rolls to rotate, said line of engagement between the spring plate and the seaming rolls being movable inwardly toward the center of the seaming head as the seaming roll moves inward in the rolling of the metal parts into the seam, whereby the surface speed imparted to the seaming rolls varies with the change in the external diameter of the double seam.

In testimony whereof, I affix my signature.
MATHEW M. SEDWICK.
